UNITED STATES PATENT OFFICE.

GEORGE TRUOG, JR., OF CUMBERLAND, MARYLAND, ASSIGNOR TO SENECA GLASS COMPANY, OF MORGANTOWN, WEST VIRGINIA, A CORPORATION OF WEST VIRGINIA.

DESIGN FOR A GLASS VESSEL.

44,717.

Specification for Design.

Patented Oct. 7, 1913.

Application filed August 11, 1913. Serial No. 784,262. Term of patent 7 years.

To all whom it may concern:

Be it known that I, GEORGE TRUOG, Jr., a citizen of the United States, and residing at Cumberland, in the county of Allegany and State of Maryland, have invented a certain new, original, and ornamental Design for a Glass Vessel, in the accompanying drawing a superficially-ornamented glass vessel being shown.

No novelty is claimed herein for the shape of the vessel.

I claim:

The ornamental design for a glass vessel, as shown.

GEO. TRUOG, JR.
